US00D639865S

(12) **United States Design Patent**
Sogabe et al.

(10) **Patent No.:** US D639,865 S
(45) **Date of Patent:** ** Jun. 14, 2011

(54) **ELECTRIC CONNECTOR**

(75) Inventors: **Takashi Sogabe**, Tokyo (JP); **Taichi Nokuo**, Tokyo (JP)

(73) Assignee: **Sony Computer Entertainment Inc.**, Tokyo (JP)

(**) Term: **14 Years**

(21) Appl. No.: **29/347,515**

(22) Filed: **Feb. 18, 2010**

(30) **Foreign Application Priority Data**

Sep. 18, 2009 (JP) D2009-021732

(51) **LOC (9) Cl.** **21-01**

(52) **U.S. Cl.** **D21/333**

(58) **Field of Classification Search** ..... D21/324-333; D14/341-347, 432, 433, 435, 217, 256; D13/133, D13/146, 147, 184, 189; 273/148 B; 463/1, 463/29-35, 46, 49; 439/180, 188, 476.1, 439/892, 894, 907, 908

See application file for complete search history.
